BUILDING TRIM

Regis W. Stalter, Pittsburgh, Pa.

Application January 21, 1950, Serial No. 139,875

2 Claims. (Cl. 20—5)

1

My invention relates to buildings whose outer walls are finished with clapboards, and more particularly to means for trimming the ends of the clapboards at the corners of such walls, as well as the edges of doorways and windows formed in the building walls.

Heretofore, many devices have been proposed to finish the corners and edges of clapboard walls, but there are certain objections to all of them. My invention consists in certain new and useful improvements in such devices, whereby greatest economy in manufacture and installation is realized, and greater architectural and structural merit are obtained.

The invention will be understood upon reference to the accompanying drawings, in which:

Fig. 1 is a fragmentary view in perspective of a small home whose windows, doors and corners are finished with a trim structure of my invention;

Fig. 2 is an "exploded" view, illustrating fragmentarily the side wall of the home at the right-hand edge of one of the windows, and showing the two components of a trim structure in positions for assembly;

Fig. 3 is a fragmentary perspective view of the two elements of the trim structure in the relative positions in which they are arranged for assembly upon the left-hand corner of the building shown in Fig. 1; and

Fig. 4 is a view similar to Fig. 3, showing the corner trim elements in position for assembly upon the right-hand corner of the building.

Referring to Fig. 1, a one-story building is shown fragmentarily. The building has four walls, the front wall 2 and one of the two side walls 3 and 4 appearing in the view. A doorway 5 and two windows 6 are provided in the front wall. The walls are faced with clapboard or lap siding formed of strips 7 applied and recured upon the outer surfaces of the inner or basal walls 8 (Fig. 2) of the building. The inner or basal walls 8 may consist of wooden boards, or composition boards, or other suitable sheeting material, carried by the usual wooden scantlings (not shown), and may have the usual liner of water-proof felt paper, or the like, applied between the inner walls and the clapboard strips 7. The clapboard siding may be formed of wooden strips, as they are shown in the drawings 50

herein. Alternately, the siding may be formed of a composition board, or of metal, such as sheet steel, aluminum, or the like; embossed or stamped to provide the stepped or lapped effect 5 when the siding is applied to the building walls.

The trim structure of this invention is designed to finish the external vertical edges of the doorway and windows of the building, in order to provide not merely the desired neat finish of the edges; but also to afford an overlapped, snug and weather-tight engagement of the trim with the clapboard siding.

It will be understood that the clapboard or lap siding, as hitherto usually applied, is butted 15 against the window, door or cover trim. In the trim structure of my invention clapboard siding strips need not be butted against the trim. More specifically, the trim of this invention is lapped over the ends of the clapboard strips; 20 giving a weather-proof job and a very neat and good-looking finish. Furthermore, the practice of my invention eliminates the waste of clapboard strips, which is usually encountered through workmen's errors in measuring and cutting the strips for snug abutment against the corner trims. Pieces of strip that are cut too short are discarded. Labor costs are reduced in the use of my trim structure, since (as will be readily perceived upon considering the drawings and 25 the ensuing specification) minute accuracy is not required; that is, the ends of the clapboard strips, being overlapped as they are by the trim structure, need not be exactly even or flush. A great deal of time of the workmen in making accurate measurements is thus saved.

The trim structure in which my invention is found comprises a basal strip 9 and a finish strip 10. Ordinarily, the trim strips 9 and 10 will be formed of wood, but aluminum, composition board, or other suitable material is held in contemplation. In application, the basal strips 9 are nailed or otherwise secured to the vertical side edges of the doorway 5 or windows 6. Referring to Fig. 2, the way in which the trim is applied to the right-hand edge of the window 6 will suffice for an understanding of how the trim is applied to both of the vertical edges of each window, and of the doorway 5 as well. The basal strip 9 is nailed upon the outer face of the inner wall or siding 8, in such position that the edge

9a is substantially flush with the edge 8a of said inner wall. The strip portion 9 extends vertically from the basal sill of the window to the top of the window opening, and a similar basal strip 9 is applied in equivalent manner to the left-hand edge of the window, which is not shown in Fig. 2, but will be understood upon reference to Fig. 1. Such basal strips 9 are applied to the vertical edges of both of the windows and the door in the particular wall (2) on which the clapboard siding is to be applied.

When the basal trim members 9 have been thus secured in place, the clapboard strips 7 are applied, with the strips cut to such length that, within the vertical extents of the doorway 5 and windows 6, the ends of the strips are positioned against, not necessarily accurately abutted against, the adjacent sides of the basal trim members 9. It is important to note that the outer faces of the basal trim members 9 are of stepped form, including a series of facets 9b, whereby the outer face of each basal trim member is of the same stepped formation as the outer surfaces of the applied clapboard strips 7. The facets 9b are laterally aligned severally with the outer surfaces of the applied clapboard strips. When the clapboard siding has been applied, the finish strips 10 are installed to complete the installation.

The finish strips 10 are of greater width than the basal strips 9, and on their inner or under faces they are of stepped form, including facets 10b which are the exact complement or counterpart of the facets 9b of the basal strips 9. The strips 10 are applied with their facets 10b snugly fitted upon the facets 9b of the basal strips 9, and with the assembled strips 9 and 10 precisely aligned at their inner edges, that is, the edges which form the vertical finish edges of the window and door openings. The strips 10 (being wider than basal strips 9) extend laterally from strips 9 and overlap the ends of the clapboard members 7, and the facets 10b of the strips 10 snugly engage the outer surfaces of the clapboard siding, forming in each instance a perfect weather-proof union 11 (Fig. 1), a union of neat and pleasing appearance.

At the inside or inner edges of the door and window openings the strips 9 and 10 meet in a pencil-line seam of saw-tooth form, as shown, which is substantially invisible, particularly after the building has been painted. The tops of the windows and doorway are finished with top trims 12, as shown, and the joints are finished by means of trim pieces 13 which in this case are flush with the inner or inside edges of the assembled trim strips 9 and 10.

The two-part trim structure 9, 10 of this invention has other advantages than those already mentioned. For example the same trim structure is adapted for use on both the right-hand and left-hand sides of the windows and doorway. It will be readily understood that the basal strips may be cut from stock milled to saw-tooth form on its outer face, as described, and the strips 9 thus cut to length may be applied to both sides of each opening to be treated. After the clapboard siding is installed, the finish strips 10, cut from stock milled to saw-tooth form on its inner face, are applied on the outer faces of the strips 9. The finish strip on the right-hand side of the opening is extended to the right from the basal strip to overlap the adjacent ends of the clapboards, while the finish strip on the left-hand side of the opening is extended to the left

of the basal strip for the same purpose. Thus, a single inventory of stock, from which strips 9 and 10 can be cut, may be carried by the mill and/or the building contractors, thereby dispensing with the necessity of stocking right-hand and left-hand parts.

The structure of the invention is also applicable with equal advantages for trimming the corners of the building. The principal modification in the structure for the corner trim 90, 100 is found in the basal member. As shown in Figs. 3 and 15, the modified basal member 90 is of saw-tooth form on two of its contiguous, longitudinal edges or faces A and B, providing on face A a line of facets 90a, on face B a line of facets 90b. By virtue of this particular form, the basal member or strip 90 may be used on any of the corners of the building. In Fig. 1 only two corners of the illustrated building are shown, the left-hand corner formed by the intersection of the walls 2 and 3, and the right-hand corner formed by the intersection of walls 2 and 4.

In applying the trim structure to the left-hand corner of the building, a basal strip 90, cut to proper length from milled stock, is applied after the clapboard siding has been installed on wall 3. The strip 90 is placed with its facets 90b overlapped upon the ends of the clapboard siding members on wall 3. The facets 90a are aligned 25 or extend severally in common planes with the outer surfaces of the clapboard siding members on front wall 2. The finish trim strip 100 may be identical in form with the finish strip 10 of the structure already described, having one edge 30 or face of saw-tooth form, with a series of stepped and inclined facets 100b that are complementary in form and arrangement with the facets 90a and/or 90b on the basal strip 90.

When the basal strip 90 has been applied to the left-hand corner of the building, as described above, the finish strip 100 is then nailed or otherwise secured upon the basal strip, with the facets 100b of the finish strip snugly engaging the facets 90a of the basal strip, as indicated at 90a, 100b at the left of Fig. 1. The finish strip is wider 40 than the basal strip, and the strip extends laterally (to the right) of the basal strip, overlapping the ends of the clapboard on front wall 2, with the extended portions of facets 100b snugly fitted upon the outer faces of the clapboard siding on said wall.

The same trim structure is used to provide the trim on the right-hand corner of the building, as will be understood upon considering Fig. 1. The trim members 90 and 100 are interchangeable as indicated in the drawings, for the finish of both right-hand and left-hand corners of any building faced with clapboard, or the like, and advantages of the nature indicated are obtained in largest measure.

Within the terms of the appended claims many modifications and variations may be made, without departure from the spirit of the invention.

I claim:

1. A trim for the corner formed by two intersecting building walls faced with clapboard siding, said trim comprising a basal strip of saw-tooth form on each of two contiguous longitudinally extending edges, one of said saw-tooth edges (hereinafter called edge "A") having facets arranged for alignment with the outer surfaces of the clapboard siding on one of said walls, the other of said saw-tooth edges having facets overlapped and fitted upon the outer surfaces of the clapboard siding on the other of said walls, and

a finish strip of saw-tooth form having facets on its inner face arranged to be secured in snug engagement with the facets of saw-tooth edge "A" and extended laterally therefrom for overlapped engagement with the outer surfaces of the clapboard siding with which the facets of said saw-tooth edge "A" are severally aligned, the engaged basal and finish strips being adapted to present in the external corner surfaces of the building a single saw-tooth seam.

2. A building structure having a wall with a 10
clapboard siding, a trim for a corner of the
building structure comprising a basal strip ex-
tending along the ends of the clapboards at said
corner, the outer face of said basal strip being
of saw-tooth form having facets located beyond 15
said ends of the clapboards and in registry
severally with the outer surfaces of the clapboard
siding, and a finish strip of saw-tooth form on

its inner face and of substantially greater width than said basal strip, the finish strip being se-
cured with its saw-tooth inner face snugly en-
gaged upon the saw-tooth outer face of the
said basal strip and extended laterally therefrom
into snug registered engagement with the outer
faces of said clapboard ends, the engaged basal
and finish strips presenting in the external corner
surfaces of the building structure a single saw-
tooth seam.
